SHEET CONTROL DELIVERY MECHANISM
FOR LITHOGRAPH, VARNISHING MA-
CHINES, AND THE LIKE

Harry W. Brintnall, San Francisco, Calif.

Application October 2, 1942, Serial No. 460,582

3 Claims. (Cl. 271—68)

This invention relates to a new and useful improvement in sheet material delivery control mechanisms and particularly relates to an especially constructed apparatus for use in connection with lithograph varnishing machines and the like for the purpose of delivering the paper sheets conveyed from the machines or the driers connected therewith into a receiving box.

The principal object of the present invention is to provide a vacuum control mechanism for automatically slowing down the travelling speed of each sheet when the same is being delivered into the receiving box whereby the sheets are uniformly piled therein.

Another object of the present invention is to provide a revolving vacuum control cylinder in combination with the sheet conveying mechanism and to convey the sheets across the outer periphery of the cylinder to the receiving box and to operate said cylinder at a slower peripheral speed than the sheet conveyor, whereby the travelling speed of each sheet is controlled and will be automatically reduced when the same is being delivered into the receiving box.

Another object of the present invention is to provide a vacuum pump and a vacuum line for causing the vacuum to be produced in said cylinder and to provide a valve in said line for controlling the timing of the vacuum in the cylinder and to further provide means for automatically controlling the operation of said valve by the travelling movement of the sheets being conveyed to the receiving box.

A further object of the invention is to provide means for automatically shutting the valve at a predetermined time whereby the vacuum will become automatically closed with respect to the cylinder before the sheet starts travelling across the outer periphery thereof, said means also causing the valve to be automatically re-opened at a predetermined time relative to the position of the sheet on the cylinder, whereby the vacuum is applied only to the rear portion of the sheet during its course of travel across the cylinder, thus preventing any possible collision of the sheets, and also controlling the positioning thereof when they are being delivered into the receiving box.

An additional object of the invention is to provide means for increasing the distance between the sheets before they reach the vacuum control cylinder, said means being preferably an auxiliary conveying mechanism associated with the primary conveying mechanism leading from the paper varnishing machine or the drier thereof,

the auxiliary conveying mechanism being adapted to receive the sheets being conveyed from said primary conveying mechanism, and is operated at a higher speed, whereby each sheet received is quickly conveyed a considerable distance away from its succeeding sheet, thus enabling each sheet to have sufficient time to be separately controlled by the vacuum cylinder.

Other objects and advantages will be apparent during the course of the following description:

In the accompanying drawings forming part of the specification and in which like numerals are employed to designate like parts throughout the several views:

Fig. 1 is a top plan view of one type of the sheets delivery mechanisms and the improvements embodying the invention;

Fig. 2 is a vertical longitudinal sectional view taken on line 2—2 of Fig. 1, looking in direction of the arrows;

Fig. 3 is an enlarged longitudinal sectional view of the vacuum control member employed in the invention;

Fig. 4 is a vertical transverse sectional view of the vacuum cylinder taken on line 4—4 of Fig. 3, looking in direction of the arrows;

Fig. 5 is an inner end elevational view of a stationary valve member associated with the vacuum cylinder;

Fig. 6 is a vertical sectional view taken through the gear casing on line 6—6 of Fig. 1, illustrating a mechanism employed for reducing the revolvable speed of the vacuum cylinder with respect to the delivery tapes;

Fig. 7 is a vertical sectional view taken through the drive gear casing on line 7—7 of Fig. 1, illustrating how the delivery tape shafts are operatively connected and,

Fig. 8 illustrates a common form of electric eye sheet detector utilized to operate the valve 51 of the device.

Referring in detail to the drawings the numeral 10 designates a plurality of endless belts that are arranged in parallelism and mounted upon suitable pulley wheels 12 and 14, respectively, the said pulley wheels being fixed to shafts 15 and 16, respectively, that are rotatably supported onto the upper portion of the conveyor frame 17. It will be noted that the said frame is suspended from a ceiling, not shown, by the vertical supports 18, 19 and 20, or can be supported on the floor 21 in any suitable manner. A plurality of other endless belts 22 are mounted on pulleys 23 and 24, respectively, and are positioned in parallelism and underneath the first mentioned belts, as

shown in Fig. 2. The conveyor proper is of conventional structure and is preferably positioned at the outer end of a series of primary conveyors leading from the machine and functions as an auxiliary conveyor for receiving the sheets from the primary conveyors, whereby the traveling speed of the sheets is increased to enable the sheets to be widely separated. The device is operated by an electric motor 25 that is operatively connected to the conveyor's pulley shaft 15 by a drive belt 26 being mounted on pulleys 27 and 28, respectively.

As hereinbefore stated one of the objects of the present invention is to provide means at the delivery end of the conveyor for decreasing and controlling the traveling speed of the sheets as they are delivered into the pile box. The preferred construction illustrated consists in providing an especially constructed cylindrical member 29 hereinafter termed the vacuum cylinder and fixing the same onto a substantial shaft 30 that is positioned in proximity to the pulleys 14 at the outer end of the conveyor and is rotatably supported in the frame 17, as shown in Figs. 1 and 2. The said cylinder 29 is preferably provided with a series of circumferential grooves 31 around the outer periphery thereof. It will be observed that each of said grooves is provided with a plurality of equally spaced holes 32 that extend radially into the cylinder, as shown in Fig. 4, and individually communicate with a series of equally spaced holes 33 that horizontally extend into the cylinder from the lateral end 34 thereof, as shown in Fig. 3.

The numeral 35 designates a substantially flat cylindrical member that is supported on a stationary bracket 36 and is longitudinally keyed thereto and is resiliently urged against the lateral face 34 of the vacuum cylinder by the coil spring 37, the bracket having an apertured angular arm 38 for enabling the spring to be compressed. An arcuate shaped port 39 is provided in the inner face of the member 35 and extends into a curved air passage-way 40, as shown in Fig. 5; a hole 41 providing an outlet for said passage-way, whereby communication is made with the air passage-way 42 provided in the bracket 36. A suitable pipe 43 forming part of the vacuum line is screwed into the lower end of said bracket and extends into the air passage-way 42.

A vacuum pump 44 is operatively connected to the motor 25 by the belt 45 mounted on the motor pulley 46 and the pump pulley 47, respectively, as shown in Fig. 2. The numerals 48, 49, 50 and 43 designate suitable pipes and numerals 71 and 72 elongated nipples provided to form the vacuum line. The numeral 51 designates a conventional magnetic valve in said line that is centrally located underneath the conveyor belts and in proximity to the rear end portion thereof. The numeral 52 indicates a thin resilient wire that leads upwardly at an angle from the valve 51, and beyond the upper face of the delivery tape 22, which carries the sheets 53 that are delivered into the receiving box 54.

The magnetic valve 51 is normally open when the resilient wire 52 is in its normal position as shown in Fig. 2 and in which position the vacuum line will be open, causing a vacuum to be produced in the cylinder 29. When the conveyed sheet passes the resilient wire 52 it moves the latter downwardly against the contact arm 55, as shown in dot and dash outline in Fig. 2, thus

closing the switch and causing the magnetic valve to be closed, whereby the vacuum produced in the cylinder 29 is closed for a limited time while the sheet is first passing over the same.

5 After the sheet passes over the resilient wire 52, the said wire springs back to its normal position re-opening the magnetic valve 51, enabling vacuum to be produced in the cylinder 29 and applied to the rear portion of the sheet. The vacuum is thus closed in the cylinder when the sheet first passes over the same and is applied to the rear portion of the sheet only, due to the relative distance between the wire and the cylinder with respect to the length of the sheets. It will 10 be apparent that the distance between the resilient wire 52 and the cylinder 29 is less than the length of the sheet to be delivered. The long nipples 71 and 72 enable the location of the magnetic valve 51 to be adjusted in the vacuum line, 15 whereby the distance between the wire 52 and the cylinder 29 can be varied.

When the cylinder 29 is revolved, the horizontal holes 33, leading into the cylinder from the lateral end 34 thereof, will successively communicate with the port 39 in the stationary member 40, enabling the air to be continuously drawn through the radially extending holes 32 at a location above the cylinder, thus causing the delivered sheet to be drawn onto the upper outer periphery thereof. The length of the arc shaped port 39 is preferably equal to the total outer distance between two of the holes 32, whereby at least one of the holes 32 will always be in communication with said port. Any suitable number of holes and size of arc shaped port can be used to best serve the purpose of the invention. A thin resilient arm 56 functions to lightly urge the sheet against the outer periphery of the cylinder.

40 It will be noted that the vacuum cylinder is revolved at a slower speed than the pulley wheels carrying the delivery tapes, in order to reduce the traveling speed of the sheets while they are being delivered into the receiving box. A suitable 45 means for reducing the speed of the cylinder is illustrated in Fig. 6 and consists in fixing a small gear 56 onto the rear pulley shaft 16 and a larger gear 57 on the cylinder shaft 30 and operatively connecting the two gears 56 and 57 by an idler gear 58 that is fixed onto a shaft 59, the said gears being enclosed in a suitable casing 60 and the shafts rotatably supported into said casing 60 and the frame 17 in any suitable manner. The shafts 45 and 61 carry the upper and lower pulley wheels 42 and 23, respectively, at the receiving end of the machine and are operatively connected by the gears 62 and 63, respectively, that are mounted into the casing 70. The difference in the diameters of the said gears 62 55 and 63 is in direct proportion to the difference in the diameters of the upper and lower pulleys 42 and 23; as a result the upper and lower delivery tapes 10 and 22 are caused to travel at exactly the same speed. The conveyor illustrated in 60 Figs. 1 and 2 represents the auxiliary conveyor and can be operated separately from the primary conveyors leading from the paper varnishing machine drier, or can be operatively connected thereto by a small pulley 64 having a belt band 65 connected to a larger pulley 66 that is fixed to one of the delivery end shafts 67 of the primary conveyors, shown in dot and dash outline in Fig. 1. In Fig. 2 there is shown a schematic view in dot and dash outline of the delivery end portion of one of the primary conveyors, illustrating

how the auxiliary conveyor is positioned to receive the sheets that are delivered therefrom. When drying the sheets conveyed from the varnishing machine it is often necessary to operate the conveyors at a slow speed in order to provide sufficient time to obtain the proper drying. It is also desirable to position the sheets on the slow conveyors with the edges of the sheets as closely together as possible in order to obtain the maximum efficiency. When this procedure is followed it becomes necessary to provide an auxiliary conveyor operating at a higher speed in order to separate the sheets a greater distance apart so that the vacuum cylinder will have sufficient time to control each sheet without any possibility of collision from the sheet following.

Any other suitable valve and means for operating the same can be employed in place of the valve 51 utilizing the resilient wire 52 for its operation. For example, an electric eye can be provided above the conveyor belts 10 and a mirror for receiving the light beam provided below the belts and positioned the proper distance from the vacuum cylinder 29. The valve would be held open by a solenoid, the circuit for which would be closed until the light beam between the eye and mirror became broken. The breaking of said beam by a sheet passing through the same would cause the circuit to become broken de-energizing the solenoid, allowing the valve plunger to drop and thus close and shut the vacuum line off from the cylinder 29. The said cylinder would thus be free from vacuum while the first portion of the sheet was passing over the same but again would be open to the vacuum line for enabling the suction to retard the latter portion of the sheet as it is being delivered into the receiving box.

It is to be understood that the forms of my invention herewith shown and described are to be taken as preferred examples of the same and that various changes relative to the material, size, shape and arrangement of parts may be resorted to without departing from the spirit of the invention or the scope of the subjoined claims.

Having thus described my invention, I claim:

1. A device of the character described for delivering sheet material into a pile, including an auxiliary conveyor for use in combination with a primary conveyor and adapted to receive sheets conveyed therefrom, means for increasing the conveying speed of the auxiliary conveyor with respect to the conveying speed of the primary conveyor, whereby the separated distance between the edges of the sheets is increased for facilitating the separate delivering of the sheets, a revolvable cylindrical member horizontally positioned in proximity to and in parallelism with the delivering end of the auxiliary conveyor, means for decreasing the speed of the cylinder member with respect to the speed of the auxiliary conveyor, and means for producing vacuum

in proximity to said cylinder member whereby the sheets are drawn on the cylindrical member while they are being delivered out of the auxiliary conveyor.

5 2. A device of the character described for delivering sheet material into a pile, including an auxiliary conveyor for use in combination with a primary conveyor and adapted to receive sheets conveyed therefrom, means for increasing the conveying speed of the auxiliary conveyor with respect to the conveying speed of the primary conveyor, whereby the separated distance between the edges of the sheets is increased for facilitating the separate delivering of the sheets, a revolvable cylindrical member horizontally positioned in proximity to and in parallelism with the delivering end of the auxiliary conveyor, means for decreasing the speed of the cylinder member with respect to the speed of the auxiliary conveyor, a series of ports extending into an end portion of the cylindrical member and through the outer periphery thereof, a vacuum line leading to said cylindrical member and having communication with said ports causing the sheets being delivered out of the auxiliary conveyor to be drawn onto the outer periphery of the cylindrical member and the delivered speed reduced, and an automatically operative valve for controlling the timing of the vacuum with respect to the cylindrical member to limit the length of time the vacuum is drawn on each sheet while the sheets are being delivered out of the auxiliary conveyor.

3. A device of the character described for delivering sheet material into a pile, including an auxiliary conveyor for use in combination with a primary conveyor and adapted to receive sheets conveyed therefrom, means for increasing the conveying speed of the auxiliary conveyor with respect to the conveying speed of the primary conveyor, whereby the separated distance between the edges of the sheets is increased for facilitating the separate delivering of the sheets, a revolvable vacuum control cylinder horizontally positioned in proximity to and in parallelism with the delivery end of the auxiliary conveyor, resilient means for guiding the sheets over the cylinder, means associated with the mechanism of the auxiliary conveyor for decreasing the peripheral speed of said cylinder with respect to the conveying speed of the auxiliary conveyor, whereby the delivery speed of the sheets is decreased, a vacuum line in communication with the vacuum control cylinder, an automatically operative valve in said line, and means associated with said valve and adapted to be operated by the sheets being delivered on the auxiliary conveyor for controlling the length of time the vacuum is in communication with said cylinder during the delivering of each sheet from the auxiliary conveyor.

60 HARRY W. BRINTNALL.
